CLAIM

The ornamental design for insect attractant cover, as shown
and described.

DESCRIPTION

FIG. 1 is a perspective view of an insect attractant cover,
showing our new design;

FIG. 2 is a top view of our new design;

FIG. 3 is a front elevational view;

FIG. 4 is a bottom view; and,

FIG. 5 is a right side elevational view, the left side being a
mirror image thereof.

The undisclosed rear view is plain and unornamented.
